[57] ABSTRACT

Covers the use of the combination of 2-imino-5-phenyl-4-oxazolidinone or a salt thereof and a potentiating agent comprising an aluminum or alkaline earth metal salt or base in treating Parkinson's disease.

6 Claims, No Drawings

2-IMINO-5-PHENYL-4-OXAZOLIDINONE AND A POTENTIATING AGENT TO TREAT PARKINSON'S DISEASE

CROSS REFERENCE TO RELATED APPLICATIONS

This application is a continuation-in-part of copending application U.S. Ser. No. 80,760, filed Oct. 14, 1970 now abandoned.

BACKGROUND OF THE INVENTION

Parkinsonism is generally characterized by involuntary tremors, diminished motor power and rigidity. The onset of the disease is insidious, with increasing rigidity or tremor or both. The patient's facial expression may be fixed or less mobile than normal; smiling spreads and slowly disappears. Body movements generally become slower. There may be gradually increased rigidity with diminished swaying of the arms during walking. Generally, the patient's legs may begin to feel stiff and excessive effort may be required to lift them from the ground while walking. Patients often assume a stooping posture and shuffle rather than walk. As the disease progresses, movements such as adjusting a tie, buttoning a coat, etc. become impossible.

The disease is usually slowly progressive and patients may live for many years. However, with increased disability, patients often become depressed, anxious, and emotionally disturbed. While treatment with various drugs such as anti-spasmodics, central nervous system stimulants and the like have been used alone or in combination to produce temporary amelioration of complaints, L-dopa was the first effective single agent in the treatment of the disease.

L-dopa has been reported to be effective against the akinesia and rigidity of Parkinsonism, particularly in extremely severe cases. An increase in mental alertness and wakefulness, relief from depression and an increase in intellect has also been observed.

While L-dopa has produced some rather promising results in experimental therapy, unfortunately it is not well tolerated by a number of patients. The most frequent side effects are nausea, vomiting, hypotension, and abnormal involuntary movements, as well as mental changes. The abnormal involuntary movements particularly pose severe problems to its continued use of approximately in 50 percent of its patients. Thus, it is evident that drugs having a minimum of unwanted complications are needed to treat patients suffering from Parkinsonism.

SUMMARY OF THE INVENTION

It, therefore, becomes an object of the invention to provide a method of treating Parkinsonism. A specific method of the invention is to provide a method of treating Parkinsonism with a drug exhibiting a low level of side effects, if any, and which does not become tolerated over extended usage. Essentially the invention here is concerned with a method of treating Parkinson's disease with a composition comprising in combination 2-imino-5-phenyl-2-oxazolidinone or a salt thereof and a potentiating agent comprising an aluminum or alkaline earth metal salt or base.

DETAILED DESCRIPTION OF THE INVENTION

In more detail, compositions found useful here in treating Parkinsonism comprise the combination of 2-imino-5-phenyl-4-oxazolidinone and a wide variety of aluminum or alkaline earth metal salts or bases. While the oxazolidinone compound itself is known to have some activity against Parkinson's disease it has been discovered here that its activity in this area may be substantially increased by combining said oxazolidinone with an aluminum or alkaline earth metal base or salt. Such potentiation of the effect of the oxazolidinone is accomplished by combination with a salt or base, despite the fact that the salt or base alone, even in relatively large dosages is substantially ineffective in this treatment area.

Typical potentiating agents include aluminum, magnesium and calcium carbonates, hydroxides, sulfates, chlorides, bicarbonates, phosphates, citrates, thiosulfates, iodides, bromides, carbonate-hydroxides, acetates, propionates, lactates, benzoates, tartrates, etc. Most preferred are magnesium salts and bases such as magnesium hydroxide, magnesium sulfate, magnesium chloride. One particularly useful composition comprises a combination of 75 percent by weight of oxazolidinone and 25 percent by weight of magnesium hydroxide, wherein approximately equimolar amounts of each are present.

In the typical situation the compositions employed here which exhibit anti-Parkinsonism activity are formed by combining one or more of the just described salts or bases with the oxazolidinone in a ratio of at least 0.05 mole of base or salt to 1 mole of oxazolidinone. While no upper limit of said ratio is to be construed, yet as a practical matter, up to about 50 or more moles of bases per mole of oxazolidinone may be combined to form useful treatment compositions.

For use in treating Parkinson's disease it may be administered in either liquid or solid form. Thus, the active compounds may be provided in granulation, tablet, capsule, elixir and other dosage forms. Oral administration is preferred and is the most convenient. Other means of administration may be employed such as, for example, by intraperitoneal or intramuscular injection. The active ingredients can also be incorporated in an oil or wax base and administered in the form of a suppository.

The compounds of the invention are found to be effective in humans at a dosage range of from about 0.1 to about 200 mg./kg. of body weight daily. More often the dose is 0.1-100 mg./kg. and most often is 1-100 mg./kg.

EXAMPLE I

One basic approach for evaluation of anti-Parkinson activity is estimating reversal of the extrapyramidal effects of reserpine which depletes biogenic amines in animals and in man, which test was employed here.

A composition comprising a mixture of 2-imino-5-phenyl-4-oxazolidinone with magnesium hydroxide (75.3 percent and 24.7 percent by weight, respectively) was prepared in a liquid form and administered to mice. The composition was found to reverse the effects of deserpentine in mice with a dosage range of 25-100 mg./kg., i.p. In another series of tests involving six

Rhesus monkeys the effects of deserpidine were reversed in an oral dose range of 5-20 mg./kg. orally.

EXAMPLE II

The above composition was also studied for its anti-Parkinson activity in additional tests. Specifically, it was studied with respect to its activity in reversing the motor activity effects of tetrabenazine (a reserpine-like drug) in mice. As is shown below, the composition demonstrated marked activity in reversing the sedative effects of tetrabenazine, which depletes brain biogenic amines.

Here the composition was made up in the form of a capsule and administered orally. The capsule mixture was composed as follows:

Composition 1

Ingredients	Grams
2-imino-5-phenyl-4-oxazolidinone	3.76
magnesium hydroxide	1.24
lactose	15.00
Total	20.00

The activity of the above composition is as follows:

TABLE 1

Test No.	Treatment	Activity Chamber Counts	t Test p Value
1	Control-tetrabenazine 5 mg./kg. i.p.	1510 ± 105	—
2	Composition 1 — 5 mg./kg. + 5 mg./kg. i.p. tetrabenazine	2213 ± 119 + 47%	0.012
3	Composition 1 — 10 mg./kg. + 5 mg./kg. i.p. tetrabenazine	2322 ± 126 + 54%	0.008
4	Composition 1 — 20 mg./kg. + 5 mg./kg. i.p. tetrabenazine	6282 ± 639 + 316%	0.003

In analyzing data from the above the table, it should be noted that in each instance the *t* test *p* value was sig-

nificantly different from the controls.

It is understood, of course, that in addition to use of the above salts or bases in combination with 2-imino-5-phenyl-4-oxazolidinone itself, salts of the oxazolidinone compound may also be employed here. This particular oxazolidinone is a relatively weak acid, and therefore salts may be formed via combination with a strong base. For example, alkali metal salts may be formed such as the sodium, lithium, etc. salts. In addition alkaline earth metal salts such as the calcium salt may also be formed. Normally, these salts are formed by reacting the oxazolidinone with a strong alkali metal or alkaline earth metal base or anhydride such as sodium hydroxide, potassium hydroxide, lithium hydroxide, calcium hydroxide etc., or sodium hydride, calcium hydride.

What is claimed is:

1. A method of treating a patient suffering from Parkinson's disease comprising the step of administering to 20 said patient at least an effective dosage of a composition comprising in combination 2-imino-5-phenyl-4-oxazolidinone or a pharmaceutically acceptable salt thereof and a potentiating agent comprising a base or salt selected from the group consisting of an aluminum base, an aluminum salt, an alkaline earth metal salt and an alkaline earth metal bases said potentiating agent being combined in a ratio of at least 0.05 mole of potentiating agent to 1 mole of 2-imino-5-phenyl-4-oxazolidinone.
2. The method of claim 1 wherein said potentiating agent is magnesium hydroxide.
3. The method of claim 2 wherein said magnesium hydroxide is combined in a ratio of about 1 mole of magnesium hydroxide to 1 mole of 2-imino-5-phenyl-4-oxazolidinone.
4. The method of claim 1 wherein said dosage range is from about 0.1 to about 200 mg./kg. of body weight daily.
5. The method of claim 4 wherein said dosage range is 0.1-100 mg./kg.
6. The method of claim 1 wherein said composition is administered in a unit dosage form in a pharmaceutically acceptable carrier, said carrier comprising a major portion of said dosage form.
